(57) **CLAIM**

The ornamental design for a cable feed-through for electric vehicles, as shown and described.

DESCRIPTION

FIG. 1 is a top-right-rear perspective view of a cable feed-through for electric vehicles showing a first embodiment of my new design;

FIG. 2 is a bottom view thereof;

FIG. 3 is a right-side view thereof;

FIG. 4 is a rear view thereof;

FIG. 5 is a left-side view thereof;

FIG. 6 is a front view thereof;

FIG. 7 is a top view thereof;

FIG. 8 is a bottom-right-rear perspective view of a cable feed-through for electric vehicles showing a second embodiment of my new design;

FIG. 9 is a bottom view thereof;

FIG. 10 is a front view thereof;

FIG. 11 is a right-side thereof;

FIG. 12 is a rear view thereof;

FIG. 13 is a left-side view thereof; and,

FIG. 14 is a top view thereof.

The broken lines in the drawings illustrate portions of the cable feed-through for electric vehicles that form no part of the claimed design.

1 Claim, 14 Drawing Sheets
